UNITED STATES PATENT OFFICE

DONALD F. WHITING, OF BROOKLYN, NEW YORK, ASSIGNOR TO WESTERN ELECTRIC COMPANY, INCORPORATED, OF NEW YORK, N. Y., A CORPORATION OF NEW YORK

ENERGIZING ELECTRON TUBES

Application filed March 15, 1924. Serial No. 899,426.

This invention relates to electron tube circuits and aims to provide improved methods and means for energizing the tubes.

A feature of the invention is the rectification of alternating currents at a voltage high enough for the efficient operation of the usual type of rectifier, and passing the rectified current in series through a low voltage device, such as a vacuum tube filament, and through a high voltage device, such as a space discharge tube.

In the specific form of the invention illustrated in the drawing and described hereinafter, the space currents for tubes of the final stages of a multi-stage amplifier are obtained by rectification and filtration of current from an alternating current source and are combined and passed through the filaments of the first stage or stages in series to heat those filaments. Moreover, current from the alternating current source lights the filaments of the final stages, and the rectifier and filter supply space current for the first stage or stages of the amplifier. Thus a single alternating current source, rectifier and filter serve to supply all of the space current and cathode heating current required for the multi-stage amplifier. Provision is made, as described hereinafter, for preventing the alternating current that heats the filaments of the final stages from causing undue disturbances in the amplifier output, and also for preventing the alternating components of the plate currents of the final stages from affecting the filaments of the first stages.

In the attached drawing Fig. 1 is a circuit diagram of one form of the invention, and Fig. 2 is a circuit diagram showing a modification of the portion of the circuit of Fig. 1 to the left of dot-dash line A—A.

Fig. 1 of the drawing shows a three-stage amplifier arranged for push-pull operation in the last stage. The first stage comprises the tube 1, the second stage comprises the tube 2, and the third stage comprises tubes 3 and 4, all of these tubes being of the three-electrode electron discharge type, and preferably, highly evacuated. An interstage transformer 5 couples tubes 1 and 2 and an interstage transformer 6 couples tube 2 to

tubes 3 and 4, which are arranged in the so-called "push-pull" relation. An input transformer 7 couples tube 1 to an incoming circuit 8, and an output transformer 9 couples tubes 3 and 4 to an outgoing circuit 10.

The filaments of the tubes 2, 3 and 4 are heated by means of alternating current supplied from an alternating current source 15, through a transformer 16, the connections from the filaments of these tubes to the grid and plate circuits being made at the mid-point of the secondary winding of the transformer 16 after the fashion disclosed in White Patent No. 1,195,632, August 22, 1916, in order to reduce the disturbances in circuit 10 due to the alternating currents in the filaments 2, 3 and 4. Since any such disturbances which might originate in the filament of tube 2 would appear in circuit 10 in augmented magnitude because of the amplification introduced by tubes 3 and 4, it is especially desirable that the effect of tube 2 in producing such disturbances be made small. This end can be furthered by reducing the voltage drop across the filament of the tube 2 to a value at least as low as 1 volt. Therefore, the filament of tube 2 is preferably a lower voltage filament than the filaments of tubes 3 and 4, equal resistances 20 and 21 being preferably connected in series with the filament of tube 2, one on each side of the filament, in order to give the current through the filament of tube 2 the proper magnitude and still avoid any necessity for special low voltage taps on the secondary winding of transformer 16.

A rectifier 25 supplies the tubes 1, 2, 3 and 4 with plate current which is smoothed out by means of a filter comprising an inductance 26 and capacities 27 and 28. The rectifier is shown in the drawing as a two electrode electron discharge rectifier but is intended to represent any suitable rectifier. The filament of the rectifier is supplied with alternating heating current from a secondary winding 30 of a transformer 31 which has its primary winding 32 connected to source 15. If desired transformers 16 and 31 may be combined into a single transformer, by put-

ting all of their windings upon a single core.

The plate current for tubes 2, 3 and 4 passes from the right hand end of a secondary winding 33 of the transformer 32, 5 through coil 26, to the point 35. Thence, the part of this current destined for tube 2 flows through primary winding of transformer 6, from the anode to the filament of tube 2, and through resistances 20 and 21 and the two 10 halves of the secondary winding of the transformer 16, to point 36. From the point 35, the plate current for tubes 3 and 4 flows through the two halves of the primary winding of transformer 9, from the plates to the 15 filaments of tubes 3 and 4, and through the two halves of the secondary winding of transformer 16 to the point 36. The plate currents for tubes 2, 3 and 4 pass from point 36 through the filament of tube 1 and a variable 20 resistance 40 shunted thereacross, through an inductance 41, from the plate to the filament of rectifier 25 and to the left hand end of winding 33. The plate currents of tubes 2, 3 and 4, passing through the filament of tube 25 1, heat that filament to the proper operating temperature.

The plate current for tube 1 passes from the right hand end of the winding 33 through coil 26, the primary winding of the transformer 5, from the plate to the filament of tube 1, through inductance 41 and rectifier 25, to the left hand end of the winding 33.

It should be noted that capacity 28 is connected in such a manner as to by-pass around 35 the filament of tube 1 the alternating components of the plate currents of the tubes 2, 3 and 4. The inductance 26 serves to prevent these currents from becoming excessive when overloading occurs in the tubes 3 and 40 4 and it also improves the push-pull action. Inductance 41 still further serves to prevent undesirable alternating current from flowing through the filament of tube 1. Inductances 26 and 41 may well be omitted in some 45 cases.

A battery 45 supplies negative potential for the grids of tubes 2, 3 and 4 and a battery 46 supplies negative potential for the grid of tube 1. However, any other suitable means 50 may, of course, be employed for supplying the proper grid potentials.

Although transformers have been shown for coupling the stages of the amplifier and for coupling the amplifier to the circuits 8 55 and 10, any other suitable coupling means may be employed.

Only three stages of amplifications are shown in Fig. 1 of the drawing, but the invention is, of course, not limited in this respect. An additional amplifier 1', if desired, 60 may, for instance, be inserted between circuit 8 and amplifier 1, as indicated in Fig. 2, with its plate circuit in parallel to the plate circuit of tube 1 and its variable resistance 65 shunt 40', in the lead between the left hand

end of shunt 40 and point 48. The function of resistances 40, 40' is to enable any desired portion of the plate currents of tubes 2, 3 and 4 to be by-passed around the filaments of tubes 1 and 1' in case the magnitude of those 70 plate currents is too great to be used as the filament heating current for tubes 1 and 1'. Similarly, a variable resistance 50 may be shunted across the plate-filament circuit of tubes 2, 3 and 4 so that the combined value of 75 these supply currents may be less than the filament heating current of tubes 1 and 1'. The resistances 40, 40' and 50 may, of course, be omitted if so desired.

The tubes 1 and 1' may be low filament current tubes, for instance, of the type commonly known as the U. V.-199, the rated filament current of which is 60 milliamperes. Tubes 3 and 4 may be, for instance, two tubes of the type known as 205-B. The plate current of 85 two such tubes, when using a plate voltage of, for instance, 350 volts, is normally about 70 milliamperes. With the tube of the second stage operating on about 8 milliamperes, for instance, there would then be 78 milliamperes available for heating the filament of tubes 1 and 1', whereas 60 milliamperes would suffice, in the case of the U. V.-199 tube.

The source 15 may be any suitable A. C. 95 source, for instance, an ordinary 110 volt, 60 cycle house lighting circuit. Transformer 16 would then usually step-down the voltage, in the direction from primary to secondary, as would also the windings 32 and 30 of transformer 31, the windings 32 and 33 of transformer 31 stepping up the voltage of source 15 to perhaps 400 or 450 volts. Thus, approximately 350 volts, for instance, would be available as plate voltage for the tubes, 100 the remainder of the 400 or 450 volts being consumed in the other elements of the space current circuit, such as the rectifier 25 and the coils 26 and 41. For the sake of simplicity, the drawing shows all of the tubes 105 receiving approximately the same plate voltage, but it is of course to be understood that a plate circuit potentiometer, such as potentiometer 50' shown in Fig. 2, or other suitable voltage changing means may be employed to apply any desired part of the available plate voltage to each of the tubes. 110

It is pointed out that the transformer 31 should be designed to deliver sufficient voltage to insure that the plate currents used to 115 heat the filament or filaments, such as the filament of tube 1, will be adequate for that purpose. For instance, if either the second or the third stage of the amplifier shown in the drawing be omitted, or if only a single 120 amplifying circuit, instead of the two push-pull connected circuits, be used in the third stage, it may in some cases be desirable to increase the plate voltage of at least one stage 125 subsequent to the first stage. In normal op- 130

eration, the D. C. space current from the tubes such as 2, 3 and 4 preferably maintains each filament of the tube 1, 1' at a temperature so high that increases of the temperature would not materially increase the plate current of tubes 1, 1'—that is the tubes 1, 1' (as well as each of the tubes 2, 3 and 4) preferably operate under the condition known as temperature saturation.

10 While the invention has been described with especial reference to its application to tandem connected amplifying stages, it is to be understood that the term "amplifier" is generic to an electron tube detector or an electron tube oscillator. Thus, the drawing is intended as representing, for instance, three tandem connected amplifier stages each delivering an output wave which is a faithful copy of the input wave for that stage; or as representing, for example, a detector at 1, and faithfully repeating wave amplifiers at 2, 3 and 4. Where another tube is inserted, ahead of tube 1, in the fashion hereinbefore described, and illustrated in Fig. 2, the additional tube may be, for instance, a faithfully repeating amplifier with tube 1 serving either as a similar amplifier or as a detector; or as is specifically shown in Fig. 2, may be, for example, a detector with tube 1 serving as a faithfully repeating amplifier; or may be, say, an oscillator, with tube 1 acting, say, as a detector.

As noted above, the rectifier 25 may be of any suitable type. It is here pointed out that even where the impedance of the rectifier is high compared to that of the filament of tube 1, that filament is heated efficiently, since the I^2R loss in the circuit through the rectifier and the filament of tube 1 occurs largely in the space current paths in tubes 2, 3 and 4.

The general principles herein disclosed may be embodied in many organizations widely different from those illustrated and described, without departing from the spirit of the invention defined in the appended claims.

What is claimed is:

1. A multi-stage electron tube amplifier circuit, one of said stages having a space current circuit, a preceding one of said stages having current responsive means for rendering said preceding stage operative, and said circuit comprising means causing said first means to render said preceding stage operative in response to said space current.

2. In combination, two electron tube amplifiers, one of said amplifiers having cathode means and a heating circuit therefor, the other of said amplifiers having a space current circuit, a source of electromotive force for supplying said space current, and means connecting said space current circuit and the first mentioned circuit in serial relation to each other across said source, said cathode means being so proportioned that in

normal operation of said amplifiers said space current heats said cathode means sufficiently to maintain said one amplifier in the temperature saturation condition.

3. The method of operating a plurality of 70 thermionic amplifiers which comprises maintaining one at the temperature saturation condition by energizing it with space current from another.

4. The method of operating two tandem 75 connected thermionic amplifiers one of which includes a push-pull amplifying stage, which comprises maintaining the cathode means of the other of said amplifiers at its normal operating temperature by the combined space 80 current of a plurality of tubes of said one amplifier.

5. In combination, an electron tube amplifier having thermionic cathode means, an electron tube amplifier having a space current 85 circuit, a source of alternating current, a rectifier, and a circuit including said rectifier, said cathode means and said space current circuit in serial relation to each other across said source, said cathode means being so proportioned as to be maintained at its normal operating temperature by said space current. 90

6. A multi-stage amplifier system comprising an electron tube amplifier having thermionic cathode means, an electron tube amplifier fed from said thermionic amplifier and having a space current circuit and including a push-pull stage, a source of alternating current, a rectifier, and a circuit including said rectifier, said cathode means and said space current circuit in serial relation to each other across said source, said cathode means being so proportioned as to be maintained at its normal operating temperature by said space current. 100

7. In combination, an electron tube amplifier having thermionic cathode means and having a space current circuit, a second electron tube amplifier having a space current circuit and having thermionic cathode means, a source of alternating current, a rectifier, a circuit including said rectifier, said first cathode means and said second space current circuit in serial relation to each other across said source, and means connecting said first space current circuit across said rectifier and said source. 110

8. In combination, an electron tube amplifier having thermionic cathode means, a second electron tube having a space current circuit and having thermionic cathode means, a source of alternating current, a rectifier, a circuit including said rectifier, said first cathode means and said space current circuit in serial relation to each other across said source, and means supplying alternating current from said source to said second cathode means, for heating said second cathode means. 120

9. In combination, an electron tube amplifier having thermionic cathode means and

- having a space current circuit, a second electron tube having a space current circuit and having thermionic cathode means, a source of alternating current, a rectifier, a circuit including said rectifier, said first cathode means and said second space current circuit in serial relation to each other across said source, means connecting said first space current circuit across said rectifier and said source, and a condenser shunted across said second space current circuit.
10. The combination set forth in claim 2, and a resistance shunted across said heating circuit.
11. The combination set forth in claim 2, and a resistance shunted across said space current circuit.
12. In combination, a thermionic electron amplifier tube having a filamentary cathode of such length, cross section and material that the normal operating voltage across the cathode terminals is at least as low as approximately one volt, a source of alternating current waves, and means for connecting said source of waves to said cathode so as to maintain across said cathode terminals said normal voltage for heating said cathode.
13. A multi-stage thermionic amplifier, one of said stages preceding the last including filamentary cathode means, a stage subsequent to said one stage including filamentary cathode means, a source of alternating current for heating both of said cathode means, and resistances for maintaining the normal filament lighting voltage across said first means at least as low as one volt.
14. In combination, a plurality of discharge tubes one of said tubes having a thermionic cathode, a source of alternating current, means for rectifying said current at a voltage high as compared with the voltage requirements of said cathode, and means for passing the rectified current serially through said cathode and through the space discharge path of another of said tubes, said current being the principal source of energy for heating said cathode.
15. The method of operating a relatively low impedance cathode and a rectifier and a space discharge path each having a relatively high impedance, which comprises energizing said cathode principally from current passed serially through said rectifier and said discharge path.
16. A multi-stage electron tube amplifier circuit, one of the stages preceding the last having a tube with a filamentary cathode of such length, cross-section and material that the tube is maintained at the temperature saturation condition by a filament voltage as low as approximately one volt, the cathodes of the tubes in the stages succeeding said one stage being such that said tubes are maintained at the temperature saturation condition by higher filament voltages, and means for heating the first mentioned cathode comprising a source of alternating current of said low voltage.
17. A system comprising two electric space discharge devices, one of said devices having a filamentary cathode, a thermionic rectifier comprising electrodes within a highly evacuated envelope, and means for supplying, from the rectified current of said rectifier, current for heating said cathode of said one device and space current for said other device, said means comprising a filter for said cathode heating current.
18. A multi-stage electron tube amplifier circuit, one of said stages having a space current circuit, a preceding one of said stages having a thermionic cathode of low impedance compared to that of said space current circuit, a rectifier tube of impedance high compared to that of said cathode and comprising an envelope having therein electrodes with a space current path therebetween, and means for supplying, from the rectified current of said rectifier, space current for the first mentioned one of said stages and current for heating said cathode, said means comprising a filter for said cathode heating current.
19. In combination, a plurality of space discharge amplifying devices each having a cathode and an anode, means for producing a space current between the cathode and anode of each of said devices, and a circuit for utilizing the space current of one of said devices to apply a unidirectional current to the cathode of another of said devices to energize said cathode.
20. In combination, a space discharge device having a cathode and anode, means for producing a space current between the cathode and anode of said space discharge device, a second space discharge device having a cathode and anode, the first-mentioned space discharge device being connected so as to feed into said second space discharge device, means for producing under control of the space current of said first-mentioned space discharge device; a space current between the cathode and anode of said second space discharge device, and means for passing the space current of said second space discharge device through the cathode of said first-mentioned device in series to energize said cathode of said first-mentioned device.
21. In combination, a high frequency receiving circuit comprising a detector and an amplifier, a current supply set comprising a source of alternating current and a rectifier therefor, a resistance in series with said rectifier and said source, and connections from said resistance for supplying plate potential to said amplifier and to said detector and filament heating current to said detector.
22. In combination, a high frequency receiving circuit comprising a detector and an amplifier, a current supply set comprising a

- source of alternating current and a rectifier therefor, a resistance in series with said rectifier and said source, and connections from said resistance for supplying plate potential to said amplifier and connections from said resistance for supplying plate potential of a different value for said detector and filament heating current to said detector.
23. In combination, a high frequency receiving circuit comprising a detector, a power amplifier and an intermediate amplifier, a current supply set comprising a source of alternating current and a rectifier therefor, a resistance in series with said rectifier and said source, and connections from said resistance for supplying plate potential of different values to said amplifiers and to said detector and filament heating current to said detector and said intermediate amplifier.
24. In combination, a high frequency receiving circuit comprising a detector and a power amplifier and an intermediate amplifier, a current supply set comprising a source of alternating current and a rectifier therefor, a series circuit including said rectifier, said source, a resistance and the filaments of said detector and intermediate amplifier, and connections from said resistance for supplying plate potentials of different values to said amplifiers and to said detector.
25. A high frequency receiving circuit comprising a detector and an amplifier, a current supply set comprising a source of alternating current and a rectifier therefor, a resistance in series with said rectifier and said source, and connections from said resistance for supplying plate potentials to said amplifier and to said detector, and filament heating current for said detector.
26. An amplification system comprising in combination a plurality of electron tubes each having a cathode, an anode and a control electrode, an input circuit for each of said tubes including said cathode and control electrode, an output circuit for each of said tubes including said anode and cathode, means interlinking the output circuit of each of said tubes with the input circuit of a succeeding tube, circuit connections to a source of alternating current, means for rectifying said current, a resistance network, connections including a filter system between said resistance network and said rectifying means, a pair of electron tubes having divided input circuits coupled with the output circuit of the last electron tube of the series, a series circuit including the cathodes of said first mentioned electron tubes and a portion of said resistance network in shunt with the space discharge path of said pair of electron tubes, connections for heating the cathodes of said pair of electron tubes from alternating current, and means connected in series with the control electrodes of said pair of electron tubes for eliminating the hum of alternating current in said receiving system.
27. An amplification system comprising in combination a plurality of electron tubes each having a cathode, an anode and a control electrode, an input circuit for each of said tubes including said cathode and control electrode, an output circuit for each of said tubes including said anode and cathode, means interlinking the output circuit of each of said tubes with the input circuit of a succeeding tube, a source of alternating current, means for rectifying said current, a resistance network, connections including a filter system between said resistance network and said rectifying means, a pair of electron tubes having divided input circuits coupled with the output circuit of the last tube of the series, a series circuit including the cathodes of said first mentioned electron tubes and a portion of said resistance network in shunt with the space discharge path of said pair of electron tubes, means for independently energizing the cathodes of said pair of electron tubes, and connections between said resistance network and the anodes of said first mentioned electron tubes for deriving differing potentials for the anodes of said first mentioned electron tubes.
28. An amplification system comprising in combination a plurality of electron tubes with the output circuit of one tube interlinked with the input circuit of a succeeding tube, each of said tubes having grid filament and plate electrodes and at least one of said tubes having larger power capacity than others of said tubes, a resistance network, connected across the output circuit of one of said last mentioned tubes, a series circuit including the filament electrodes of a number of said tubes, said series circuit being connected in series with a portion of said resistance network whereby the current supply to said filament electrodes and the output circuit of said tube of larger power capacity is governed by said resistance network.
29. An amplification system comprising in combination a plurality of electron tubes with the output circuit of one tube interlinked with the input circuit of a succeeding tube each of said tubes having grid, filament and plate electrodes and at least one of said tubes having larger power capacity than the others of said tubes, a resistance network, a series circuit containing the filament electrodes of the tubes of less power capacity than said first mentioned tube, and a circuit including the plate electrode of said larger power capacity tube connected in series with a portion of said resistance network, said resistance network being shunted across the plate circuit of said larger capacity tube.
30. An amplification system comprising in combination a plurality of electron tubes with the output circuit of one tube interlinked

with the input circuit of a succeeding tube, a pair of electron tubes having their input circuits coupled with the output circuit of said first mentioned tubes each of said tubes having grid, filament and plate electrodes, 5 said pair of electron tubes having larger power capacity than said first mentioned tubes, an impedance network, and a series circuit including the filaments of said first mentioned tubes in series with a parallel connection between a portion of said impedance network and the plate electrodes of 10 said larger power capacity tubes.

31. An amplification system comprising in combination a plurality of electron tubes with 15 the output circuit of one tube interlinked with the input circuit of a succeeding tube, each of said tubes having grid, filament and plate electrodes and at least one of said tubes 20 having larger power capacity than the others of said tubes, a series circuit containing the filament electrodes of the tubes of less power capacity than said last mentioned tube, said series circuit including the plate electrode 25 of one of said tubes of larger power capacity and a resistance network having a portion thereof connected in shunt with the series circuit including the filament electrodes of the tubes of less power capacity than said 30 last mentioned tube.

32. An amplification system comprising in combination a plurality of electron tubes with the output circuit of one tube interlinked with the input circuit of a succeeding tube, a pair 35 of electron tubes having larger power capacity than said first mentioned electron tubes, each of said tubes having grid, filament and plate electrodes, said pair of electron tubes having a larger power capacity than 40 said first mentioned electron tubes, with the plate electrodes thereof connected in parallel, with respect to the plate current supply, a resistance network, a series circuit including the filament electrodes of said first mentioned electron tubes and a portion of said resistance network, and connections between 45 said resistance network and the plate circuits of said pair of larger power capacity electron tubes.

50 In witness whereof, I hereunto subscribe my name this 13th day of March, A. D. 1924.
DONALD F. WHITING.
